Harold F. Randall

UNITED STATES PATENT OFFICE.

HAROLD F. RANDALL, OF TIFFIN, OHIO.

DRAWING-MACHINE.

1,325,802.

Specification of Letters Patent. Patented Dec. 23, 1919.

Application filed May 1, 1918. Serial No. 231,930.

To all whom it may concern:

Be it known that I, HAROLD F. RANDALL, a citizen of the United States, residing at Tiffin, in the county of Seneca, State of Ohio, have invented a new and useful Drawing-Machine, of which the following is a specification.

My invention relates to a machine for the mechanical drawing of letters and figures by means of prepared tracing patterns including mechanism for controlling the movement of a drawing pen and means for regulating the size of the drawing.

The specification is accompanied by two drawings, Figures 1 and 2.

Fig. 1, is a perspective view of the machine and Fig. 2, is a side elevation of the same.

Similar letters refer to similar parts throughout both views.

Referring to the accompanying drawings, the rod A, is suspended from the supporting standard B by the flexible joint C (preferably a ball joint) which provides for the movement of the lower extremity of the rod and allows the tracing point D, which is movably sleeved on the rod, to follow the lines of the tracing pattern M. The horizontal bar E, with its side extensions, F, F, is supported by the swinging arm G, and by pivotally connected hangers H, H, and is thus confined to a horizontal movement, causing the drawing pen attached to the hinged holder I, and the post J to maintain a vertical position. This arrangement also eliminates friction and resistance in the movement of the bar and members.

As shown in Fig. 1, the arm G, swings on pivot bearings N, N. The bar E, is connected by a pivot O, with the arm. The ends

of the hangers H, H, turn on pivots, P, P, and Q, Q, extending respectively from the side extensions and the supporting standard overhead.

The holder I, is hinged by pivot bearings R, R, to the side extensions which allows a vertical movement of the pen. The socketed member K, carrying the ball joint L, is movable on the post. The rod A passes through the ball member of the ball joint, which is movable on the rod, thus providing for the raising or lowering of the ball joint, by means of which the size of the drawing, compared with the pattern, is regulated.

By means of the mechanical combination above described, a given movement of the tracing point is made to impart a proportional movement to the drawing pen. Thus, for example, by following the lines of the tracing pattern with the tracing point the pen is made to produce a drawing that will correspond to the pattern.

I claim:

In a drawing machine, a vertical rod suspended from a supporting standard by a flexible joint, a tracing point, having a socketed extension, movable on the rod, a horizontal bar having at one end side extensions, a swinging arm supporting the other end of the bar, hangers supporting the side extensions, a holder with a drawing pen attached thereto and hinged to the side extensions, a post attached to the side extensions, a socketed member movable on the post, a ball joint movable on the rod, and connecting it with the socketed member, and means for removably carrying tracing patterns under the tracing point.

HAROLD F. RANDALL.
